PROCESS FOR THE ISOMERIZATION OF
HYDROCARBONS

John Anderson, Berkeley, Sumner H. McAllister,
Lafayette, and William E. Ross, Berkeley, Calif.,
assignors to Shell Development Company, San
Francisco, Calif., a corporation of Delaware

Application December 23, 1940, Serial No. 371,306

15 Claims. (Cl. 260—683.5)

The present invention relates to a new and improved method for the isomerization of hydrocarbons and, more particularly, saturated hydrocarbons containing from four to nine carbon atoms. A particular aspect of the invention relates to a method whereby commercial hydrocarbon fractions comprising saturated hydrocarbons having at least four carbon atoms and boiling in the gasoline boiling range may be continuously and more economically isomerized in the liquid phase with a minimum of side reactions and maximum catalyst life.

As is well known, the various saturated hydrocarbons having at least four carbon atoms can exist in a number of isomeric modifications. Thus, the paraffinic hydrocarbons from butane to nonane can exist in the following number of isomeric forms:

Butane	2
Pentane	3
Hexane	5
Heptane	9
Octane	18
Nonane	35

Notwithstanding the large number of isomeric modifications generally possible, these hydrocarbons as found in natural sources such as petroleum occur almost exclusively in the normal or slightly branched modifications.

A few of the lower saturated aliphatic hydrocarbons, such as butane and pentane, are used to a considerable extent in organic syntheses, etc. By far the most important application of these hydrocarbons is, however, in fuels for internal combustion engines. Studies of the chemical properties and ignition characteristics of a large number of the possible isomers have shown that certain isomeric modifications are vastly superior to others for these purposes, and that, in general, the naturally-occurring isomers are the least preferred. Normal pentane, for example, is obtained in large quantities from petroleum. It is chemically quite unreactive and, in view of its poor ignition characteristics, is a poor fuel component for internal combustion engines. The branched modification, isopentane, on the other hand, is much more chemically reactive and may be readily condensed with olefinic hydrocarbons by an alkylation process to produce saturated higher molecular weight hydrocarbons having excellent ignition characteristics. Isopentane is, furthermore, an exceptionally valuable fuel component per se, especially for aviation fuels. In view of the vastly superior properties

of isopentane over normal pentane and, in general, more highly branched hydrocarbons over less branched hydrocarbons, a commercially practical method for the conversion of normal pentane to isopentane and for converting the large available quantities of less desirable less branched hydrocarbons to their more highly branched isomers is very desirable.

It has long been known that certain acid-acting metal halides, such as catalysts of the Friedel-Crafts type, exert a strong catalytic influence in hydrocarbon reactions. Aluminum chloride, for example, is one of the most powerful cracking and polymerizing catalysts known and is widely used in the cracking of petroleum hydrocarbons into lower boiling hydrocarbons and the polymerization of olefines to synthetic lubricating oils. The aluminum halides when in the presence of a hydrogen halide are known to also catalyze the isomerization of saturated hydrocarbons under certain conditions. Consequently, considerable work has been done in attempts to provide a practical isomerization process employing these agents. With the exception of the isomerization of n-butane to isobutane, however, the various attempts have met with very little success. Butane, although less reactive, is quite stable and can be treated quite satisfactorily in the vapor phase with certain solid promoted aluminum chloride catalysts. In the case of normal pentane and all higher boiling hydrocarbons, however, it appears necessary to resort to liquid phase treatment. In the liquid phase treatment several problems arise which have so far not been overcome. Thus, the catalysts quickly attack certain small to appreciable quantities of hydrocarbon types and impurities invariably present in commercial hydrocarbon feeds with the formation of tarry materials which coat the catalyst particles and cause them to agglomerate into relatively inactive thick tarry masses. This, of course, is not confined to the isomerization of paraffin hydrocarbons but takes place likewise in various other processes such as alkylation, polymerization, etc. when using aluminum halide catalysts. In certain of these processes this difficulty has been minimized to some extent by applying, instead of aluminum chloride or aluminum bromide, certain complex addition compounds thereof. For example, it has been proposed to employ complex addition compounds of the Gustavson and Ansolvo-acid types in which aluminum chloride or aluminum bromide is bound by secondary valence bonds to one or more organic compounds. These complex compounds

are normally liquid and the catalyst cannot therefore agglomerate into hard sticky lumps.

It has also been proposed in certain cases to employ complex double salts of aluminum chloride and aluminum bromide such as those produced by reacting aluminum chloride or aluminum bromide with such salts as the halides of Na, K, Li, NH₄, Ca, Mg, Ba, Ag, Cu, etc. These double salts are normally solid compounds of relatively high melting point and low volatility. They are usually impregnated into a porous carrier material such as pumice, diatomaceous earth or the like, and employed in the solid state. In some cases, however, where high reaction temperatures are practical, it has also been proposed to employ them in their fused or molten state.

While these substitutes for aluminum chloride and aluminum bromide have certain applications wherein they minimize or prevent the agglomeration of the catalyst into inactive masses and are advantageous in certain processes such as the polymerization of olefines, they are entirely unsuited for practical application in the isomerization of saturated hydrocarbons. The isomerization of saturated hydrocarbons, although catalyzed by aluminum chloride and aluminum bromide (in the presence of a hydrogen halide), differs from the alkylation of aromatic hydrocarbons, the polymerization of olefines, etc. in certain important respects. The isomerization of saturated hydrocarbons, for instance, is a very difficult reaction to effect in a practical way and is catalyzed only by a very few selected catalysts: Thus, although the isomerization of certain saturated hydrocarbons to small extents has been noted with such catalysts as zirconium chloride, beryllium chloride and molybdenum sulfide under very severe conditions, the only catalysts so far known to effect the isomerization in anything like a practical way are aluminum halides in the presence of a hydrogen halide. Alkylation, polymerization, etc., on the other hand, are reactions which are easily effected with any number of catalytic agents including, for instance, the acids of phosphorus, sulfuric acid, zinc chloride, iron chloride, certain acid clays, etc. It is, therefore, not surprising that the above-described complex compounds of aluminum chloride and aluminum bromide, although effective for certain of these other reactions, are relatively ineffective in the isomerization of saturated hydrocarbons.

The reason for the low order of activity of these complex compounds and their inability to effectively catalyze the isomerization of saturated hydrocarbons is apparent when it is considered that the active catalyst in the isomerization of saturated hydrocarbons with aluminum chloride and aluminum bromide is not aluminum chloride or aluminum bromide per se, but acid compounds thereof such as HAlCl_4 and HAlBr_4 . Thus, it has long been known that aluminum chloride and aluminum bromide will catalyze the isomerization of saturated hydrocarbons only when promoted by a hydrogen halide. In the above-described complex compounds of aluminum chloride and aluminum bromide the secondary valence forces required to produce the desired acid compounds are saturated by the other constituent of the complex and little or no active acid compound can form.

The primary object of the present invention is to provide a more advantageous method whereby saturated hydrocarbons may be effectively isomerized in a practical manner with liquid catalysts. A more particular object is to provide

a more advantageous method for the isomerization of pentane in the liquid phase. Another more particular object is to provide a more advantageous method for the vapor phase isomerization of butane. Still another more particular object is to provide a practical and highly efficient method whereby the anti-knock characteristics of low boiling saturated hydrocarbon fractions of the nature of gasoline may be appreciated with a minimum consumption of catalyst and minimum degradation. Several distinct advantages of the present process, the realization of which are further objects of the invention, are referred to below in the description of the process.

These objects, we have found, may be realized by treating the appropriate hydrocarbons and/or hydrocarbon fractions under isomerizing conditions with the aid of certain liquid aluminum halide catalysts in which an aluminum halide is combined to a substantial extent with a hydrogen halide as a hydrogen aluminum halide or "aluminic acid." Thus, the isomerization is effected with the aid of fused catalysts comprising an aluminum halide-hydrogen halide compound such as HAlCl_4 and a metal halide which does not react with the aluminum halide either by addition or metathesis. Catalysts of this type are described and claimed in our copending application, Serial No. 363,676, filed October 31, 1940, of which the present application is a continuation-in-part.

While other aluminum halides may be employed in the present process, anhydrous aluminum chloride is preferred. Aluminum chloride is less expensive, is substantially insoluble in the hydrocarbon reactants, and may be employed with a wider variety of metal halides.

By employing with the aluminum halide only metal halides (by which term we mean to include double halides and mixtures of metal halides) which do not react therewith, the secondary valence forces of the aluminum halide are preserved for the formation of the desired hydrogen aluminum halide. As a consequence, when these fused mixtures are treated with hydrogen halide, much larger quantities of the active acid compounds are formed and excellent isomerization results.

The melting point-composition diagrams of binary mixtures of the more common metal halides with aluminum chloride and aluminum bromide have been determined. In most cases, therefore, it is known which metal halides react with the aluminum halides and which do not. Thus, such metal salts as the halides of Na, K, Li, NH₄, Ag, Cu, Ca, Mg, Ba, etc. are per se unsuited and specifically excluded since they form stable double salts of the type described above with the corresponding aluminum halides. Since the metal halides employed do not react with the aluminum halide employed, their mixture with the aluminum halide will form simple eutectics or mixed crystals which can be easily identified by a simple melting point-composition curve.

In view of the considerable differences in properties between the various aluminum halides, whether or not a particular metal halide, double halide, or mixture of halides is suitable will depend to a considerable extent upon the particular aluminum halide employed. Thus, for example, antimony trichloride is a preferred metal halide when employed with aluminum chloride. Antimony tribromide, on the other hand, cannot be employed per se with aluminum bromide since it

forms a double salt of the formula, $\text{AlBr}_3 \cdot \text{SbBr}_3$, therewith. As examples of metal halides which may be employed with one or more of the aluminum halides may be mentioned the halides of As, Zr, Nb, Mo, Pd, Sn, Sb, Hf, Ta, W, Tl, Pb, Bi, and U.

While, in general, the catalyst may be prepared with any metal halide or mixture of metal halides which does not react with the aluminum halide, the catalysts prepared with certain metal halides are much superior in the present process than others. Thus, for example, we prefer to employ metal halides or metal halide mixtures having normal boiling points below about 300° C. Catalysts prepared with these metal halides or mixtures of metal halides are much more advantageous in the present process than catalysts prepared with metal halides having higher normal boiling points in several important respects. For example, when catalysts prepared with these lower boiling metal halides are employed, the used catalyst may be easily recovered and reactivated by a simple distillation treatment, whereas when catalysts prepared from higher boiling metal halides are employed this is practically impossible, and more expensive and inefficient methods must be resorted to. Also, when catalysts prepared from these lower boiling metal halides are employed the isomerization reactions may be executed at much lower temperatures. This is of particular advantage in the isomerization of saturated hydrocarbons since at lower temperatures the equilibrium between the normal and branched chain isomers is much more favorable and higher conversions may be obtained. Also, of the various available metal halides and mixtures of metal halides employed we generally prefer to choose those which are less soluble in the hydrocarbons involved. While this is not essential, it may allow the isomerization to be effected somewhat more economically. It is to be noted, however, that metal halides which act as halogenating agents are generally unsuited. For this reason, the applicable halides of the metals generally contain the metal in a lower valent state. A preferred metal halide which gives exceptionally desirable catalytic agents with the preferred aluminum halide, aluminum chloride, is antimony trichloride. This metal halide when employed alone or in admixture with other suitable metal halides yields excellent catalysts which are generally superior in their high activities, low solubilities in most reactants, low melting points, low boiling points, and high densities.

In order to effect the isomerization at a practical rate under practical conditions, the aluminum halide should comprise at least 3 mol per cent of the fused halide mixture. Since, furthermore, it is often advantageous to effect the isomerization at appreciably elevated temperatures, it is preferable to limit the activity of the catalyst by employing a molecular excess of the metal halide, i. e. at least one plus mols, and preferably two or more mols, of metal halide or mixture of metal halides for each mol of free aluminum halide. This is important since if catalysts are employed having a molar excess of free aluminum halide with respect to the other metal halide or mixture of metal halides, they become too vigorous in their action after being treated with a hydrogen halide and when used in a molten state may cause undesirable side reactions, such as degradation, almost exclusively. The relative amounts of the respective metal halides in the catalyst will depend

upon the melting point and activity desired in the resulting catalyst. In general, it is desirable to employ mixtures corresponding to or approaching the eutectic mixture. In such cases, however, where the eutectic composition does not contain sufficient free aluminum halide and consequently gives catalysts of lower-than-desired activity, or contains excessive amounts of free aluminum halide and consequently gives catalysts of higher-than-desired activity, the composition may be adjusted to yield a catalyst having the desired activity and a slightly higher melting point. Thus, for example, excellent catalysts may be prepared from mixtures comprising from about 76 to 97 mol per cent antimony trichloride and 24 to 3 mol per cent aluminum chloride. These prepared from mixtures containing about 9 mol per cent free aluminum chloride are of about the optimum activity and melt to free-flowing liquids at about 70° C. The activity may be increased, however, if desired, by employing mixtures containing more free aluminum chloride, in which case the melting point of the catalyst is increased somewhat.

As explained above, in order to catalyze the isomerization of these saturated hydrocarbons, it is necessary that the catalysts comprise the active acid compounds of the aluminum halide. In order to form these active compounds the fused mixture of metal halides may be treated in any suitable manner with a hydrogen halide prior to use. The active acid compounds may also be formed conveniently during the isomerization by supplying a hydrogen halide to the reaction mixture during the reaction. Thus, the hydrogen halide may be added during the process as a liquid, gas or solution. The necessary hydrogen halide may, moreover, be generated in the reaction zone, if desired, by introducing a material which will decompose or react under the prevailing conditions to form hydrogen halide. Suitable materials which may be added for this purpose are, for example, chlorine, bromine, boron fluoride and organic halides such as tertiary butyl chloride.

In general, we prefer to employ the hydrogen halide corresponding to the aluminum halide employed. Thus, when employing aluminum chloride, the preferred hydrogen halide is anhydrous hydrogen chloride.

The hydrogen halide may be employed with the hydrocarbon feed in amounts from as low as about 0.5 weight per cent up to about 10-25 weight per cent. When higher concentrations of hydrogen halide such as 3% to 8% are employed, it is usually desirable to recover and recycle the excess hydrogen halide.

It is to be noted that, unlike the complex catalyst hitherto proposed for other purposes, the catalysts employed in the present process do not hinder or prevent the formation of the hydrogen aluminum halide compounds but allow these compounds to form and exist in a maximum concentration. Thus, for example, a fused metal halide mixture containing about 6% of aluminum chloride when treated with hydrogen chloride may react to convert from about 5% to 40% of the aluminum chloride to the active hydrogen chloride double compound. The concentration of the hydrogen halide-aluminum halide double compound actually produced in the catalyst depends, of course, upon the partial pressure of hydrogen halide above the catalyst, higher partial pressures of hydrogen halide forming higher concentrations of the double compound and increasing the isomerizing activity

of the catalyst. A substantial amount of hydrogen halide may also be taken up in the metal halide mixture by solution. This tends to increase the effective partial pressure of hydrogen halide in contact with the aluminum halide and favors the formation of the desired active addition compounds. If, for example, 408 grams of normal butane containing about 2% HCl is treated with about 400 grams of a fused catalyst containing about 95% SbCl₃ at a temperature of about 80° C. and a pressure of about 240 p. s. i., it is found that about 2.46 grams of HCl are absorbed by the catalyst. About 1 gram of the absorbed HCl (or about 40%) is dissolved in the catalyst and may be removed by simple extraction or blowing with nitrogen, whereas about 1.44 grams (or about 60%) of the absorbed HCl are retained and are most difficult to remove.

The process of the invention is generally applicable for the isomerization of saturated hydrocarbons such, for example, as butane, pentane, hexane, heptane, octane, cyclohexane, dimethyl cyclopentane and the like. It is particularly advantageous for the isomerization of commercial normally liquid saturated hydrocarbons and saturated hydrocarbon fractions having from four to nine carbon atoms and boiling in the gasoline boiling range, preferably below 70° C. The hydrocarbon treated need not necessarily be a pure individual hydrocarbon but may be a mixture of two or more hydrocarbons. Thus, the invention provides a practical process for converting to isopentane the normal pentane content of commercial hydrocarbon mixtures such as are obtained from natural gas, petroleum distillates, and from cracking higher molecular weight hydrocarbons. Conveniently treated normal pentane-containing mixtures are the so-called amylene-pentane fractions from which the olefines have been substantially removed. The treatment of such mixtures which usually contain only small amounts of isopentane results in very materially increasing their isopentane content and enhancing their value as raw materials in the production of isopentane, alkylation products, aviation gasolines, etc. Technical pentane fractions such as those containing from 70% to 80% normal pentane and from 30% to 20% isopentane may be treated in accordance with the process of the invention and their isopentane content increased up to about 90% without appreciable loss of pentane due to decomposition and while realizing a maximum active life of the catalyst. The process is also especially adapted for the improvement of the ignition characteristics of light gasoline fractions such as cuts of straight run gasoline which may or may not contain pentane.

The hydrocarbon or mixture of hydrocarbons treated is, however, preferably substantially free of easily polymerizable materials. Olefines, if present in any appreciable amount, not only tend to polymerize but may also alkylate the saturated hydrocarbon with the formation of undesirable higher boiling products. According to the preferred embodiment of the invention, any olefines or other detrimental impurities in the charge stock are removed prior to use by a suitable treatment, such as treatment with sulfuric acid or by hydrogenation.

In order to realize the advantages of the molten catalysts employed in the present isomerization process the isomerization must obviously be executed at temperatures at least as high as the melting point of the mixtures of metal halides

employed. In the treatment of butane the isomerization is preferably executed at temperatures below about 200° C. and usually below about 125° C. In the treatment of gasoline fractions somewhat lower temperatures; for instance, temperatures below about 130° C. and usually below about 110° C. are preferred. One advantage of the present isomerization process is that when recycling the catalyst through the reaction zone the desired temperature may be conveniently maintained by adjusting the temperature of the recycled molten catalyst. This is not usually possible in other processes using the double salts mentioned above since these salts are usually too high melting to be employed in the fused state. Also, it is not practical when using the above-described organic complexes since these are easily converted to coke by heating. The desired temperature in the reaction mixture may also, of course, be maintained in any conventional manner.

When executing isomerization reactions with aluminum chloride per se, it is usually necessary to employ considerable pressures in order to minimize the loss of catalyst by volatilization. In the present process this is not usually necessary and ordinary pressures may be employed. When operating in the preferred manner wherein the hydrocarbon treated is in the liquid phase, however, a sufficient pressure is employed to maintain the hydrocarbon in the liquid phase. Thus, for example, at the more usual operating temperatures, pressures in the order of from about 1.5 to 20 atmospheres absolute are generally sufficient. These pressures may be produced by the hydrocarbon vapor, or may be produced by the addition of inert gases such as methane, hydrogen, nitrogen or the like.

Under the above-described conditions the isomerization takes place at a very practical rate with a minimum amount of side reactions. The reaction time required depends upon the material being isomerized, the conversions desired, the prevailing temperatures and the efficiency of contact with the catalyst.

When operating with efficient agitation at temperatures in the order of 70°-120° C. excellent conversions may be obtained with quite short contact times and high throughput rates may be realized. In view of the high activity of the catalysts employed in the present process care should be exercised that the reaction conditions (i. e. contact time, temperatures and pressure) are not chosen to severe. In all cases, and especially in such cases where the hydrocarbon or mixture of hydrocarbons treated contains materials which are susceptible to other reactions under the influence of Friedel-Crafts catalysts, the reaction conditions are adjusted to avoid excessive side reactions.

The process may be executed either in the vapor phase or liquid phase. In the vapor phase process the molten catalyst may be continuously recycled down through one or more reaction towers, preferably provided with baffle plates or filled with an inert packing material, while the hydrocarbon vapors pass countercurrent thereto. The process is most advantageous, however, for the treatment of normally liquid hydrocarbons in the liquid phase. This may be effected in any of the conventional ways, including for example by batch autoclave treatments, by continuous or semi-continuous autoclave treatments, by concurrent or countercurrent passage of the hydrocarbon and molten catalyst through reaction

towers, and by circulating the reaction mixture through reaction coils or tubes under appropriate conditions.

Particularly appropriate methods which have been developed for effecting the isomerization according to the process of the invention are illustrated in the attached flow diagram wherein a suitable arrangement of apparatus is shown diagrammatically. The process illustrated in the flow diagram is adapted for the treatment of casinghead gasoline and similar commercial fractions of saturated hydrocarbons and involves preliminary separation of the hydrocarbon fraction into sub-fractions which are then each treated in the most suitable manner, the lower boiling or normally gaseous fraction being isomerized in the vapor phase and the higher boiling fraction being treated in the liquid phase. It is to be noted that it is not essential that both of the treatments be effected and that either of the treatments (i. e. the vapor phase isomerization of the lower boiling fraction or the liquid phase isomerization of the higher boiling fraction) may be effected alone. The hydrocarbon feed comprising essentially saturated hydrocarbons is first fed to a suitable fractionating apparatus 1 wherein it is separated into a lower boiling overhead fraction, preferably consisting essentially of butane, and a higher boiling bottom or debutanized fraction. The overhead fraction is refluxed in a suitable fractionating apparatus 2 to separate isobutane. The bottom fraction consisting largely of normal butane is fed via pump 3 through suitable heat exchangers 4 and 5 to the treating chamber 6. It will be noticed that the product from the treater is fed into fractionator 2 as well as the overhead fraction from the fractionator 1. Thus, fractionator 2, as shown, serves a double purpose. This is a most advantageous arrangement. In such cases where the overhead fraction from fractionator 1 contains substantial quantities of non-isomerizable hydrocarbons and in such cases where it is desired to include pentane in the lower boiling fraction from fractionator 1, at least one more fractionating apparatus is required and the flow must be altered somewhat. This will be readily apparent to those skilled in the art. The feed preheated to the desired temperature in heat exchangers 4 and 5 enters reactor 6 near the bottom in the vapor phase, passes up, preferably through a suitable packing such as carbon saddles, countercurrent to the fluid catalyst, and leaves the reactor near the top. It (the isomerate) is then cooled in heat exchangers 6 and 7 and collected in the liquid phase in separator 8. The liquid condensate is pumped from separator 8 via pump 9 to a fractionating column 10. The vapors from said separator 8 consisting largely of hydrogen chloride saturated with hydrocarbons is also pumped to fractionator 10 by a compressor 11. It will be noticed that the isomerate is first cooled sufficiently to condense the major portion of the hydrocarbon and then the condensate and vapors are each separately fed to fractionator 10. There are alternative methods of effecting this step. One is to cool the isomerate further and then feed the total condensate to fractionator 10 by a suitable pump. Another is to compress the gaseous isomerate to substantially liquefy same. The method illustrated, however, is considerably more efficient than either of these other methods. In fractionator 10 the considerable quantities of hydrogen chloride are separated from the hydro-

carbon isomerate. The separated hydrogen chloride is removed overhead and recycled to reactor 6, entering the latter with the hydrocarbon feed. A small amount of the overhead from fractionator 10 may be vented via outlet 12 in order to avoid the accumulation of excessive quantities of non-condensable inert gases. The hydrogen chloride required in the process may be conveniently produced in a small generator such as illustrated near the top of the flow diagram. Thus, concentrated sulfuric acid from a storage tank 13 is fed to a column 14, packed with a loose inert filler such as pumice or the like. Muriatic acid from storage tank 15 is fed to column 14 at a somewhat lower point. Dilute sulfuric acid is continuously withdrawn from the bottom of the column, and the generated hydrogen chloride is withdrawn from the top to a storage tank 16. The hydrogen chloride is fed into the recycled hydrogen chloride from the overhead from fractionator 10 by a small compressor 17. The hydrocarbon isomerate from fractionator 10 is preferably passed through a caustic scrubber 18 and then is returned to fractionator 2, as described above. In this way substantially pure isobutane may be recovered from fractionator 2; none of the isobutane present in the feed is passed through the reactor; and any unisomerized normal butane in the isomerate is recycled through the system. Thus, this method effects a complete and continuous isomerization with a minimum of apparatus. In reactor 6 the fluid catalyst, such as described above, is introduced at the top and withdrawn from the bottom, being recirculated via pump 20 through a suitable heat exchanger 21. Catalyst to be regenerated may be intermittently or continuously withdrawn to a regenerating retort 22. In retort 22 the metal halide is distilled from any alumina, etc. and collected in a suitable receiver 23. After adjusting the concentration of aluminum chloride in the catalyst in receiver 23, the regenerated catalyst is pumped via pump 24 back to pump 20 in the reactor system.

The bottom fraction from fractionator 1 is preferably re-fractionated in a suitable fractionating apparatus 30. The fractionation in fractionator 30 is preferably adjusted to collect as an overhead product a fraction which is most susceptible to appreciation by the isomerization treatment. As will be noted from the results quoted below it is often found that whereas a total fraction is improved only slightly by an isomerization treatment, certain fractions thereof may be greatly improved. If the hydrocarbon fraction is first fractionated, part isomerized, and then the fractions reblended, a much greater improvement in octane number is usually therefore possible. Also, this method considerably reduces the amount of material to be treated in order to effect a given octane number increase. In practice we have found that the overhead from fractionator 30 should usually boil up to about 70° C., although in some cases somewhat higher end points such, for instance, as 130° C.-150° C. are quite suitable. The higher boiling bottom product from fractionator 30, which material is usually not substantially appreciated by an isomerization treatment, is withdrawn from the system and may, if desired, to be reblended with the isomerate. The condensate from fractionator 30 is pumped via pump 31 to reactor 32, being introduced near the bottom concurrent with the liquid catalyst. The product from treater 32, which in this case comprises both the isomerate

and liquid catalyst, is withdrawn from the top and stratified in separator 33. The catalyst (lower layer) is withdrawn from the bottom, passed through a suitable heat exchanger and recirculated through the reactor 32 via pump 34. Reactor 32 is preferably provided with some means for insuring intimate contact between the two immiscible liquid phases and the gas phase such, for instance, as an inert solid porous material, baffle plates, or the like. The hydrocarbon and gas phase collected in separator 33 is withdrawn from the top and passes to a stripping column 35. A small amount of gases may be vented via outlet 36. The larger quantity of hydrogen chloride is pumped back to the reactor via pump 37, entering with the hydrocarbon feed. Make-up hydrogen chloride, generated as described above, is fed to the recycle system via compressor 17. The bottom product from stripper 35 is fed to a fractionating column 38 where in hydrocarbon isomerate is taken off overhead. The overhead product (isomerate) is passed through a caustic scrubber 39 and is withdrawn from the system. The bottom product from fractionator 38 consists largely of a minor amount of metal halides. It may be returned to reactor 32 via pump 41 or may be withdrawn as described above and distilled in retort 22. The regenerated catalyst may be returned to reactor 32 via pump 24.

An important advantage of the present process is that no sludge of the usual type is formed and that substantially all of the aluminum halide employed is efficiently utilized. A small amount of sludge consisting almost exclusively of spent aluminum halide complexes (probably compounds in which one or more of the halogen atoms of the aluminum halide have been replaced by organic radicals) and tar-like polymers is formed, but this material does not appear to affect either the product or the catalyst.

The catalyst, if not fortified from time to time by the addition of aluminum halide, gradually loses its activity due to the exhaustion of the aluminum halide in the molten mixture. After a long period of use, usually with periodic adjustment of the aluminum halide concentration, it may become contaminated with small amounts of metal oxides due to the decomposition of the metal halides by small amounts of moisture, etc. This does not affect the catalytic activity in any way but may eventually affect the viscosity of the melt and cause pumping troubles. When metal halides having normal boiling points below about 300° C. are employed with the aluminum halide they may be recovered substantially free from these and any other impurities by simply distilling them.

The present process for the isomerization of saturated hydrocarbons is particularly advantageous in view of the high conversions obtainable at quite moderate temperatures and pressures. For instance, in one experiment eighteen batches of a 98% n-butane fraction were treated at a hydrocarbon to catalyst ratio of 5:1, temperature of 80° C. and contact time of 30 minutes under a partial pressure of hydrogen chloride of 40 p. s. i., and a conversion of 46% to 47% isobutane was obtained throughout with no perceptible decrease in catalytic activity between the first and last treatment. Also, there was no apparent sludging. Analysis of the catalyst after the eighteen treatments showed only 0.3% carbon. In another experiment employing a temperature of about 100° C., the conversion to iso-

butane was 41.5% with a contact time of only 10 minutes. By increasing the contact time to 20-30 and 60 minutes the conversions to isobutane were 56%, 60.5% and 63%, respectively. Even higher conversions may be obtained if better contact is employed. Thus, for example, using a hydrocarbon to catalyst ratio of 10:9 at a temperature of 90° C., a 52% conversion to isobutane may be obtained with 10 minutes contact, and with 20 minutes contact the conversion may be increased to 63.5%.

The above-quoted conversions obtainable in the isomerization of a relatively pure butane illustrate the exceptional isomerizing ability of the catalysts employed in the process, since butane is quite unreactive and is one of the most difficult hydrocarbons to isomerize at a practical rate. In view of this inertness, however, butane is perhaps the easiest hydrocarbon to isomerize without causing excessive side reactions. From a practical point of view, therefore, the most difficult hydrocarbons to isomerize are the higher paraffin hydrocarbons and, in particular, commercial hydrocarbon fractions such as aviation base stocks and the like. These materials, when treated by prior methods, are invariably degraded and entail severe catalyst sludging and poor conversions. The present process, however, in view of its relative freedom from sludging difficulties is exceptionally advantageous for the treatment of such distillates. Thus, by way of example, a few of the distillates which have been successfully reformed (isomerized) by the present process and the change in octane number effected by such treatment are the following:

	Boiling range	Initial octane number (C. F. R.)	Final octane number (C. F. R.)
Pennsylvania straight run gasoline fraction	• C. 15-70	68.5	83.5
High octane hydrogenated aviation gasoline base stock fraction	20-70	81.3	84.6
East Texas straight run gasoline fraction	Up to 70	72.5	83.0
Ventura straight run gasoline fraction	Up to 70	73.5	85.5
California aviation base stock	20-135	73.0	76.0
California aviation base stock (fraction of above)	20-88	77.0	81.5
Illinois straight run gasoline fraction	70-150	17.5	22.5

The fact that the catalyst when spent may be easily freed of contaminating impurities, refortified and reused is a particular advantage in the present process, especially in the treatment of commercial hydrocarbon fractions such as the above where small amounts of impurities, etc. tend to shorten the catalyst life. Thus, as an illustrative example of the recovery of a used catalyst, a used antimony trichloride-aluminum chloride catalyst containing about 3.9% carbon as impurities was flash-distilled from a retort. 92% of the catalyst was recovered. The analytical data on the used catalyst, the recovered catalyst, and the residue were as follows:

	Used catalyst	Recovered catalyst	Residue
Per cent	Per cent	Per cent	
Sb	44.9	80.7	13.2
Al	2.0	0.2	12.2
Cl	47.0	48.8	48.7
C	3.9	0.1	15.4

The small amount of antimony retained in the residue can, of course, be recovered, if desired,

by dissolution. The recovered catalyst is re-fortified with fresh aluminum chloride to the desired concentration and is then equivalent in every respect to the freshly prepared catalyst.

In the foregoing and in the appended claims, for purposes of determining the specified mol ratios, the aluminum halides are considered to have the general formula, $Al(Hal)_3$.

We claim as our invention:

1. A process for the isomerization of butane which comprises contacting butane in the substantial absence of olefins under isomerization conditions at a temperature below about 200° C. at which the catalyst is in a molten state with an isomerization catalyst consisting of a molten mixture comprising from about 76 to about 97 mol portions of antimony trichloride, about 3 to about 24 mol portions of aluminum chloride, and hydrogen chloride.

2. A process for the isomerization of butane which comprises contacting butane in the substantial absence of olefins under isomerization conditions at a temperature below about 200° C. at which the catalyst is in a molten state with an isomerization catalyst consisting of a molten mixture comprising aluminum chloride, hydrogen chloride and antimony trichloride, the mol ratio of antimony trichloride to aluminum chloride being at least 2:1.

3. A process for the isomerization of butane which comprises contacting butane in the substantial absence of olefins under isomerization conditions at a temperature below about 200° C. at which the catalyst is in a molten state with an isomerization catalyst consisting of a molten mixture comprising aluminum chloride, hydrogen chloride and antimony trichloride, the antimony trichloride being in molecular excess with respect to the aluminum chloride.

4. A process for the isomerization of butane which comprises contacting butane in the substantial absence of olefins under isomerization conditions at a temperature below about 200° C. at which the catalyst is in a molten state with an isomerization catalyst consisting of a molten mixture comprising aluminum chloride, hydrogen chloride and a chloride of another metal which does not react with the aluminum chloride under the isomerization conditions, the latter metal chloride being in molecular excess with respect to the aluminum chloride.

5. A process for the isomerization of butane which comprises contacting butane in the substantial absence of olefins under isomerization conditions at a temperature below about 200° C. at which the catalyst is in a molten state with an isomerization catalyst consisting of a molten mixture comprising an aluminum halide, a hydrogen halide and a halide of another metal which does not react with the aluminum halide under the reaction conditions, the latter metal halide being in molecular excess with respect to the aluminum halide.

6. A process for the isomerization of pentane which comprises contacting pentane in the substantial absence of olefins under isomerization conditions at a temperature below about 130° C. at which the catalyst is in a molten state with an isomerization catalyst consisting of a molten mixture comprising from about 76 to about 97 mol portions of antimony trichloride, about 3 to about 24 mol portions of aluminum chloride and hydrogen chloride.

7. A process for the isomerization of pentane which comprises contacting pentane in the sub-

stantial absence of olefins under isomerization conditions at a temperature below about 130° C. at which the catalyst is in a molten state with an isomerization catalyst consisting of a molten mixture comprising aluminum chloride, hydrogen chloride and antimony trichloride, the mol ratio of antimony trichloride to aluminum chloride being at least 2:1.

8. A process for the isomerization of pentane which comprises contacting pentane in the substantial absence of olefins under isomerization conditions at a temperature below about 130° C. at which the catalyst is in a molten state with an isomerization catalyst consisting of a molten mixture comprising aluminum chloride, hydrogen chloride and a chloride of another metal which does not react with the aluminum chloride under the isomerization conditions, the latter metal chloride being in molecular excess with respect to the aluminum chloride.

9. A process for the isomerization of pentane which comprises contacting pentane in the substantial absence of olefins under isomerization conditions at a temperature below about 130° C. at which the catalyst is in a molten state with an isomerization catalyst consisting of a molten mixture comprising an aluminum halide, a hydrogen halide and a halide of another metal which does not react with the aluminum halide under the isomerization conditions, the latter metal halide being in molecular excess with respect to the aluminum halide.

10. A process for isomerizing hydrocarbons which comprises treating a saturated hydrocarbon fraction boiling essentially below 70° C. in the substantial absence of olefins under isomerization conditions at a temperature below about 130° C. at which the catalyst is in a molten state with an isomerization catalyst consisting of a molten mixture comprising from about 76 to about 97 mol portions of antimony trichloride, about 3 to about 24 mol portions of aluminum chloride and hydrogen chloride.

11. A process for isomerizing hydrocarbons which comprises treating a saturated hydrocarbon fraction boiling essentially below 70° C. in the substantial absence of olefins under isomerization conditions at a temperature below about 130° C. at which the catalyst is in a molten state with an isomerization catalyst consisting of a molten mixture comprising aluminum chloride, hydrogen chloride and antimony trichloride, the mol ratio of antimony trichloride to aluminum chloride being at least 2:1.

12. A process for isomerizing hydrocarbons which comprises treating a hydrocarbon fraction consisting essentially of saturated hydrocarbons having from 4 to 9 carbon atoms in the substantial absence of olefins under isomerization conditions at a temperature below about 200° C. at which the catalyst is in a molten state with an isomerization catalyst consisting of a molten mixture comprising from about 76 to about 97 mol portions of antimony trichloride, about 3 to about 24 mol portions of aluminum chloride and hydrogen chloride.

13. A process for isomerizing hydrocarbons which comprises treating a hydrocarbon fraction consisting essentially of saturated hydrocarbons having from 4 to 9 carbon atoms in the substantial absence of olefins under isomerization conditions at a temperature below about 200° C. at which the catalyst is in a molten state with an isomerization catalyst consisting of a molten mixture comprising aluminum chloride, hydrogen

chloride and antimony trichloride, the mol ratio of antimony trichloride to aluminum chloride being at least 2:1.

14. A process for isomerizing hydrocarbons which comprises treating a hydrocarbon fraction consisting essentially of saturated hydrocarbons having from 4 to 9 carbon atoms in the substantial absence of olefins under isomerization conditions at a temperature below about 200° C., at which the catalyst is in a molten state with an isomerization catalyst consisting of a molten mixture comprising aluminum chloride, hydrogen chloride and a chloride of another metal which does not react with the aluminum chloride under the isomerization conditions, the latter metal chloride being in molecular excess with respect to the aluminum chloride.

15. A process for isomerizing hydrocarbons which comprises treating a hydrocarbon fraction consisting essentially of saturated hydrocarbons having from 4 to 9 carbon atoms in the substantial absence of olefins under isomerization conditions at a temperature below about 200° C. at which the catalyst is in a molten state with an isomerization catalyst consisting of a molten mixture comprising an aluminum halide, a hydrogen halide and a halide of another metal which does not react with the aluminum halide under the isomerization conditions, the latter metal halide being in molecular excess with respect to the aluminum halide.
